UNITED STATES PATENT OFFICE.

ALONZO B. CHOATE AND LOUIS J. PICHA, OF ST. PAUL, MINNESOTA.

AMUSEMENT DEVICE.

1,410,372.

Specification of Letters Patent. Patented Mar. 21, 1922.

Application filed December 19, 1919. Serial No. 345,963.

To all whom it may concern:

Be it known that we, ALONZO B. CHOATE and LOUIS J. PICHA, citizens of the United States, residing, respectively, at St. Paul, 5 in the county of Ramsey and State of Minnesota, have invented a new and useful Amusement Device, of which the following is a specification.

The object of this invention is to provide 10 an amusement device for children which can be used as a coaster, the parts of said device being separable so that it can serve a number of purposes. A further object is to construct said parts so that they are inexpensive and strong and so that they are easily 15 and quickly attached or detached, the mode of attachment and construction being strong and rigid so that the entire device will withstand severe use such as toys and amusement 20 devices are subjected to when in use. More particularly this invention is provided with a knee rest, a handle bar, a foot rest and a bundle carrier, of which all or any number can be used simultaneously at will and 25 can be selectively positioned at different elevations so as to accommodate the device for use by children of different sizes. With these and other objects in view our invention 30 comprises the features of construction and combination of parts hereinafter more particularly described and claimed.

In the accompanying drawing forming part of this specification, Fig. 1 is a perspective view of our invention; Fig. 2 is a 35 longitudinal section of a detail taken on the line 2-2 of Fig. 1; Fig. 3 is a perspective view of the bundle carrier; Fig. 4 is a perspective view of the knee rest, and Fig. 5 is a section of a detail taken on the line 40 5-5 of Fig. 2.

In the drawing let A indicate the base or body of the device, which is in the form of a long narrow plate having the single roller 2 journaled below its forward end and a 45 pair of antifriction rollers 3 journaled below its back end, all of which are secured to its lower face and upon which the device is adapted to run freely. B indicates the staff which is substantially vertical although 50 this position is not essential as it may be arranged slightly inclined to the base if so desired. The lower end of this staff is secured to the base by the brackets 4 and by a tongue and groove connection 5 (see 55 Fig. 5). The staff is mounted back of the forward supporting roller 2 so as to im-

part greater stability to the device when in use and so that the device will not tip forwardly easily as if the forward roller support were positioned directly below or back 60 of the staff.

Mounted immediately adjoining the lower end of the staff is a horizontal foot support 6 which is in the form of a bar let into the staff by any one of the horizontal grooves 7 and secured to the staff by the readily detachable bolt 8. Thus the foot rest can be selectively positioned in elevation on the staff in any one of the grooves 7. The 65 grooves 7 prevent the foot rest from turning on its bolt 8 and cooperate with the bolt in locking the rest firmly on the staff.

Arranged above the foot rest is a knee rest C which resembles a bracket having a horizontally arranged plate or bar 9 extending rearwardly a short distance from the staff and above the foot rest, and a downwardly extending plate 10 which is adapted to rest against the back face of the staff. 70 The two members 9 and 10 are reinforced in 75 strength by the angularly disposed brace 11 which assists in producing a strong and rigid knee rest structure. The plate 10 is provided with a horizontal tongue 22 on its front face which is adapted to fit into any 80 one of the horizontal grooves 12 in the back face of the staff, there being a plurality of 85 said grooves arranged at different elevations. The knee rest may be adjusted on the staff at different elevations, as desired, to 90 accommodate the device for use by different sizes of children. The plate 10 is clamped upon the staff by means of the readily detachable bolt 13, the shank of which extends through the vertical slot 14 in the staff so 95 that the knee rest can be moved with its tongue entering any one of the grooves 12 by loosening the bolt but without entirely removing it. The tongue and groove connection between the knee rest and bracket 100 and the broad face bearing produced by the plate 10 against the staff produces a strong and rigid separable connection.

Arranged above the knee rest is a horizontal handle bar D which may be seated in any 105 one of the series of slots 15 in the staff to assist in holding it upon the staff. This handle bar is additionally fastened upon the staff by the readily removable bolt 16 the shank of which passes through the handle 110 bar and through a vertical slot 17 in the staff. Thus by positioning the handle bar in

any one of the slots 15 and securing at selective elevation by means of the bolt 16, the device can be used more readily by children of different heights, the slot 17 permitting 5 the handle bar when the bolt 16 is loosened to be moved into any one of the slots 15 without entirely disconnecting the handle bar from the staff. Obviously the knee rest can be used by a small child as a seat while 10 a larger child simultaneously rides and propels the device.

When desired a bundle carrier E in the form of a receptacle can be secured at selective elevation on the front of the staff, 15 a vertical slot 18 being provided in the back wall 19 of the carrier, through which the same bolt 13 which secures the knee rest on the staff can be passed to simultaneously fasten the bundle carrier in position. The 20 bundle carrier is also provided with a horizontal tongue 20 on the back face of the wall 19, which is adapted to enter any one of the horizontal slots 21, in the front face of the staff. In this manner the bundle carrier 25 receptacle is interlocked on the staff in such manner that it will not turn and a strong and rigid connection is provided. The slot 14 in the staff and the slot 18 in the bundle carrier permit independent adjustment at 30 relative elevation of the knee rest and bundle carrier. The entire structure due to its construction is strong, rigid, durable and inexpensive to produce.

In accordance with the patent statutes we 35 have described the principles of operation of our invention together with the apparatus which we now consider to represent the best embodiment thereof, but we desire to have it understood that the construction shown is 40 only illustrative and that the invention can be carried out by other means and applied to uses other than those above set forth within the scope of the following claims.

Having described our invention, what we 45 claim as new and desire to protect by Letters Patent is:—

1. An amusement device, comprising, in combination, a base, antifriction carrier elements arranged below the forward and back

ends of said base, a staff mounted upon the 50 forward end of said base back of said forward carrying element and a handle member upon the upper end of said staff, bolt and slot connections by which said handle member is detachably secured to said 55 staff at any one of a number of selected elevations, a foot rest secured to the lower end of said staff, and a knee rest resembling a bracket having a broad side resting against the back face of said staff, said broad side 60 and staff having a tongue and groove connection and a fastener securing said bracket and staff together with said tongue and groove interconnected.

2. An amusement device, comprising, in 65 combination, a base having antifriction carrier elements arranged below its forward and back ends, a staff mounted upon the forward end of said base back of said forward carrying element, said staff having a series 70 of transverse slots and a vertical slot, intercepting said transverse slots, a handle bar adapted to be seated in any one of said transverse slots, a bolt passing through said bar and through said vertical slot to detachably secure the handle bar upon said staff while seated in any one of the transverse slots, a knee rest resembling a bracket having a broad side resting against the back face of said staff, said broad side and staff 75 having a tongue and groove connection, a fastener securing said bracket and staff together with said tongue and groove interconnected and a bundle carrier detachably mounted upon said staff.

3. An amusement device, comprising, in 80 combination, a base having antifriction carrier elements arranged below its forward and back ends, a staff mounted upon the forward end of said base, and a knee rest 85 resembling a bracket having a broad side resting against the back face of said staff, said broad side and staff having a tongue and groove connection and a fastener securing said bracket and staff together with said tongue and groove interconnected.

ALONZO B. CHOATE,
LOUIS J. PICHA,
